United States Patent Office.

CHARLES EDWIN BACON, OF BUFFALO, NEW YORK, ASSIGNOR TO HIMSELF AND GEORGE A. PRINCE.

Design No. 4,700, dated March 14, 1871.

DESIGN FOR AN ORGAN-CASE.

The Schedule referred to in these Letters Patent and making part of the same.

I, CHARLES EDWIN BACON, of Buffalo, in the county of Erie, and State of New York, assignor to myself and George A. Prince, of same place, have invented and produced a new and original Design for a Reed-Organ Case, of which the following is a specification.

The accompanying photographic illustration shows the nature and form of the invention, and letters of reference designate the different parts.

General Description.

The invention relates to the original shape and configuration of the case of the instrument, as shown in the accompanying drawing.

In the photograph—

A A show the front corners, which round out and project from the front face, thereby taking away the flat, square look, and greatly increasing the beauty of the whole case.

The upper part of these corners or their tops are raised a little way above the action, giving the instrument a more graceful appearance, and leaving open spaces a a' each side of the music-rack, in which rest the ornamental candle or lamp-stands B B, and which are firmly fastened to the instrument, the whole clearly shown in Figure 2.

b b are the ornamental brackets or side abutments, as clearly shown, which take off the flat look of the sides, making the case more pleasing to the eye.

I claim—

The design for reed-organ cases, as shown.

In witness whereof I have hereunto signed my name in the presence of two subscribing witnesses.

CHAS. E. BACON.

Witnesses:

J. R. DRAKE,
C. N. WOODWARD.
